Andrew L. Chezem ATTORNEY.

UNITED STATES PATENT OFFICE.

EDWARD T. E. MANGELS AND ERWIN G. MANGELS, OF DAVENPORT, IOWA.

DINING CABINET.

Application filed April 18, 1925. Serial No. 24,021.

Our invention relates to improvements in dining cabinets which are provided with table and benches, and capable of being folded and closed up, and also capable of 5 being used as an independent article of furniture, or of being inserted in, or attached to a wall, in such manner as to give the appearance of being an entrance to another room; and the objects of our improvement are, first, to provide a cabinet suitable 10 to be installed in rooms which have not been especially built for that purpose; second, to provide a dining apartment which may be folded up in such way, as to utilize space, 15 and at the same time furnish a needed accessory in a room; third, to furnish an article of utility capable of reducing the labor of housewives.

We attain these objects by the mechanism 20 illustrated in the accompanying drawing, in which—

Figure 1 is an elevation taken at an angle partly in perspective of the open cabinet, with its members unfolded; Fig. 2 is a perspective view of the cabinet with its doors open and members folded; Fig. 3 is a perspective view of the cabinet taken at an angle with its members folded and its doors closed; Fig. 4 is an elevation of a broken portion of one of the seat members, disclosing its connecting means; Fig. 5 is an elevation of a broken portion of the table member disclosing the connection of the table and support.

Similar numerals refer to similar parts throughout the several views.

Sides 1^a and 2, top 4, and back 3 of cabinet 1 constitute the framework of our invention; line 33 being a floor line. The cabinet being composed of sides 1^a and 2, top 4 and back 3, its height is usually constructed conformable to the door or window openings of a room.

To the front edges of sides 1^a and 2, by ordinary hinge means is attached a pair of door members 5 and 6 of suitable width to close the front of cabinet 1, but to the outer edges of door members 5 and 6 by hinge means, we attach folding screen sections 7 and 8, having panels corresponding to the panels of door members 5 and 6, and of a height conformable to door members 5 and 6, said screen sections 7 and 8 being so fixed as to fold inwardly upon door members 5 and 6, and which said folding screen sections 7 and 8 are of suitable width to unite

with door members 5 and 6 when unfolded in spreading the entire length of benches 14 of said cabinet 1, when said benches 14 are unfolded and their ends 14^a let down 60 to the floor, in so screening said benches 14 from view as to give the cabinet 1 a room effect, in privacy and appearance, but when said folding screen sections 7 and 8 are folded inwardly against door members 5 and 6, they are out of the way, unobservably enclosed inside of cabinet 1, and when door members 5 and 6 are closed it gives the cabinet 1 the appearance of being the entrance 65 to another room.

In the top board 4 of cabinet 1, and so suitably centrally disposed therein, as to swing inwardly out of the way of door members 5 and 6, we have secured a lamp fixture 31, composed of a swinging crane 75 supporting a lamp, which crane 31 is of suitable length, when swung out, to centrally suspend lamp 32 directly suitably over the table 9, when table 9 is unfolded into using 80 position. Said lamp fixture is composed of an arm 31, of any ordinary material and has reverse right angular extremities, with ordinary connecting threads and holes therein, and is so bent to enable it in swinging to clear the elevated end of table member 9^a and bench seats 15 as shown in Fig. 2, when they are upwardly folded, and yet permit a light 32 supported on one end thereof, to extend downwardly.

We have attached said lamp fixture by a 90 plate 31^c hung to the top of the cabinet, but in other form of arm it may be attached elsewhere in the cabinet, as to the side or back.

Unto the inside of back 3 of cabinet 1, 95 positioned suitably from its bottom and centrally disposed, by leaf hinge means 24, we attach a table top 9^a at one of its ends, in such manner that the table top may be folded snugly upwardly against the said back 3, or let down for use operatively with support 10, attached thereto, and to the other end of said table top 9^a, we attach said table end support 10 by hinge means 100 13, in such manner that when top 9^a is upwardly folded against back 3, said end support 10 folds downwardly against the under side of top 9^a. For sanitary purposes support 10 has its bottom end centrally curved into leg effect 10^a, showing thus two legs, and for convenience in being seated to it, has portions 14^a, 14^b and 14^c of its front

edge 10^b cut away. Top 9^a is centrally provided on its under surface at its outer end in proximity to the point of rest upon support 10 with a spring latch 30, suitable for engaging in connecting means 30^a conformably provided in the top end of support 10, for holding support 10 in place, when table top 9^a is folded up.

Unto the inside of back 3 of cabinet 1, on 10 either side of table top 9^a, we attach the ends 15^a of bench seats 15, by multiple hinge means 25 in such manner that said bench seats 15 may be folded upwardly against back 3 or let down for use operatively with 15 bench ends 14, provided therefor on the outer ends of bench 15.

Bench ends 14 each have a portion of their tops 14^a and 14^b cut away to form arm rests and to enable the users to more conveniently 20 get their bodies in and out by table top 10, and they likewise have a portion of their bottom parts cut away at 14^c to enable the users to more conveniently get their feet in and out by the foot of table support 10.

25 Bench ends 14 are respectively operatively attached unto the outer ends of bench seats 15 by multiple hinge means 23 and 24 in such way as to allow the bench ends 14 to fold and unfold outwardly as the bench seat 15 is 30 raised unto or lowered away from the back of cabinet 3, the purpose being obvious.

To the back sides of bench seats 15 by 35 multiple hinge means, we attach seat backs 22 in such manner that when the tops of bench ends 14 are tilted outwardly, the seat backs 22 will fold forward upon bench seats 15, and be carried upward against cabinet back 3, in folding, and be unfolded for use as directed, when the bench seat 15 is again 40 lowered.

To facilitate the folding of backs 22 upon bench seat 15, against cabinet back 3, the multiple hinges 25 used are prepared with

long curved upper leaves to provide space for folding.

To secure said seat backs 22 to seat ends 14 and the cabinet back 3 to prevent its falling backward, we have provided suitable hasps and latches 26, but the rear end of the back may rest against the inside of side 50 boards 1 and 2, with safety.

Seat back 22 is shown composed of slats 16, 17, 18, 19, 20, and 21, but the same may be constructed of any suitable material.

Other hinges 28 are shown beside 27 for 55 the purpose of illustrating that any number of hinges may be used as desired.

We claim:

In a cabinet of the class described, a bench member having a seat hingedly attached to 60 the inside of the back of said cabinet in such manner that said seat may be folded upwardly against said cabinet back, a seat back hingedly secured to one of the edges of said seat in such manner as to forwardly fold 65 upon said seat, an end seat brace, hingedly secured near the middle of its linear dimension to an end of said seat in such manner as to fold outwardly against the bottom of 70 said seat when said seat is raised; hasp fastening means secured upon the outer end of said seat back, an upper end of said seat brace capable of co-operatively securing the 75 said seat back to the said seat brace, other hasp fastening means secured upon said cabinet back and top end of said seat brace capable of co-operatively securing said 80 bench to said cabinet back, said seat end having portions of its front edge and its bottom end cut away to facilitate its use, all 85 for the purposes specified.

Done at the city of Davenport, in the county of Scott and State of Iowa, this fifteenth day of April, A. D. 1925.

EDWARD T. E. MANGELS.
ERWIN G. MANGELS.
